CLAIM

The ornamental design for a hearing-aid set as shown and described.

DESCRIPTION

FIG. 1 is a perspective view of a hearing-aid showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is a perspective view of a box for hearing-aid thereof;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof.

FIG. 17 is a perspective view of the hearing-aid case in an open state; and,

FIG. 18 is Perspective view of the combination of the hearing-aid and box for hearing-aid.

The broken lines in the drawings depict portions of the hearing-aid set that form no part of the claimed design.

1 Claim, 18 Drawing Sheets
